(57) **CLAIM**

The ornamental design for a picture light, as shown and described.

DESCRIPTION

FIG. 1 is a front, left and top perspective view of a picture light, showing my new design;

FIG. 2 is a rear, right and bottom perspective view thereof;

FIG. 3 is a front view thereof;

FIG. 4 is a rear view thereof;

FIG. 5 is an enlarged left side view thereof;

FIG. 6 is an enlarged right side view thereof;

FIG. 7 is a top view thereof;

FIG. 8 is a bottom view thereof;

FIG. 9 is an enlarged view of portion “9” of FIG. 2 thereof; and,

FIG. 10 is an enlarged view of portion “10” of FIG. 2 thereof.

The broken lines shown in the drawings illustrate portions of the picture light that form no part of the claimed design. The dot-dash broken lines depict the boundaries of the enlargements that form no part of the claimed design.

1 Claim, 10 Drawing Sheets
